US0D1035020S

(12) **United States Design Patent** (10) **Patent No.:** **US D1,035,020 S**
(45) **Date of Patent:** **** Jul. 9, 2024**

(54) **THERMAL PACK**

(71) Applicant: **KOBAYASHI PHARMACEUTICAL CO., LTD.**, Osaka (JP)

(72) Inventors: **Yuuki Nonomura**, Ibaraki (JP); **Hirokazu Watanabe**, Ibaraki (JP)

(73) Assignee: **KOBAYASHI PHARMACEUTICAL CO., LTD.**, Osaka (JP)

(**) Term: **15 Years**

(21) Appl. No.: **29/867,830**

(22) Filed: **Nov. 10, 2022**

(30) **Foreign Application Priority Data**

May 17, 2022 (JP) ..... 2022-010449 D

(51) **LOC (14) Cl.** **24-01**

(52) **U.S. Cl.**

USPC **D24/206**

(58) **Field of Classification Search**
